DISPLAY ENVELOPE FOR CERAMIC TILES OR SIMILAR ARTICLE

Leonard H. Sager, Levittown, N.Y., assignor to Soriano
Ceramics, Inc., Long Island City, N.Y., a corporation of New York

Application April 29, 1958, Serial No. 50,668

Term of patent 14 years

(Cl. D80—5)

FIG. 2

FIG.3

Fig. 1 is a side elevational view of a display envelope for ceramic tiles showing my new design;

Fig. 2 is a front elevational view thereof;

Fig. 3 is a rear elevational view thereof;

Fig. 4 is a top plan view thereof.

The broken line showing of the tile in Fig. 3 is for illustrative purposes only.

I claim:

The ornamental design for a display envelope for ceramic tiles or similar article, as shown and described.
